UNITED STATES PATENT OFFICE.

WALTER A. JACOBS, OF MOUNT VERNON, AND WADE H. BROWN, MICHAEL HEIDELBERGER, AND LOUISE PEARCE, OF NEW YORK, N. Y., ASSIGNEES TO THE ROCKEFELLER INSTITUTE FOR MEDICAL RESEARCH, OF NEW YORK, N. Y., A CORPORATION OF NEW YORK.

ARSENICAL COMPOUND.

1,280,124.

Specification of Letters Patent. Patented Sept. 24, 1918.

No Drawing. Original application filed October 3, 1917, Serial No. 194,459. Divided and this application filed January 16, 1918. Serial No. 212,116.

To all whom it may concern:

Be it known that we, WALTER A. JACOBS, Ph. D., residing at Mount Vernon, Westchester county, New York, WADE H. BROWN, M. D., residing at Flushing, in the city of New York, borough of Queens, county of Queens, New York, MICHAEL HEIDELBERGER, Ph. D., residing in the city of New York, borough of Manhattan, county and State of New York, and LOUISE PEARCE, M. D., residing in the city of New York, borough of Manhattan, county and State of New York, all citizens of the United States, have jointly invented a new and Improved Arsenical Compound, of which the following is a specification, this being a division of our application, Serial No. 194,459, filed October 3, 1917.

We have found, in the course of our chemical and biological researches, that, whereas the well-known substance chemically designated as N-phenylglycin-p-arsonic acid corresponding to the following formula and described in D. R. P. 204664

25

30

is of little therapeutic value in the treatment of trypanosomal or spirochaetal infections, when the COOH group of this compound is 35 transformed in the manner to be described below into the carboxamid or CONH₂ group, resulting in a compound which may be designated as N-phenylglycinamid-p-arsonic acid corresponding to the following formula:

45

50 a remarkable change in the biological properties occurs which is shown by the striking

increase in the curative power of this new arsenical compound in the treatment of such infections. We have found in general that substances of this type, which are characterized by the possession of a glycinamid or RNH₂CH₂CONH₂ group (R, as seen below, referring to aromatic arsonic acid in general), are powerful therapeutic agents. Thus, we have found that similar results are obtained by the use of the homologues of the above substance, such as the N-tolylglycinamid-p-arsonic acids, and N-xylylglycinamid-p-arsonic acids, and also of the isomers of these substances in which the arsonic acid or AsO₃H₂ radical is situated in the ortho or meta position to the glycinamid group. We have also found that other compounds belonging to the new type of therapeutically valuable arsenicals, are obtained when the glycinamid or aminoacetamid radical is changed to homologues such as the α -aminopropionamids,

75

80

or the α -aminophenylacetamids,

85

90

in which, as in the above-mentioned substances, the α -amino group is joined to the phenyl-p-arsonic acid residue or its homologues or isomers.

We have further found that by replacing in the above-mentioned substances one or both of the hydrogens of the amid group by an alkyl as shown in the following formulæ,

where R may be methyl, ethyl, propyl or benzyl or substituted benzyl

5

10

or

15

20

that this general type of therapeutically important substances are still further extended.

As arsonic acids, all the above-described 25 substances are readily soluble in the equivalent amounts of alkali or alkali carbonates, and when so treated form neutral and stable solutions of their salts.

Substances of the types above described 30 were obtained in two ways:

1. By the interaction of the corresponding aminophenyl arsonic acid, or preferably its salt, in aqueous or in dilute alcoholic or acetone solution with the corresponding 35 α -halogenacylamid, and when necessary with a hydriodic acid salt, as a catalyst.

2. By the reaction of the phenylglycin ester arsonic acid with ammonia or an amine, or by any of the other usual methods for 40 converting the COOH group into the CONR_2 group, where R is hydrogen or alkyl.

We shall now describe the preferred 45 methods for the preparation of these substances.

Example I.—N-Phenylglycin amid-p-arsonic acid.

217 grams of p-aminophenylarsonic acid 50 are dissolved in one liter of normal sodium or potassium hydroxid solution. 187 grams of chloracetamid (or the equivalent amount of bromo or iodo acetamid) are added and the mixture boiled under a reflux for one 55 half to one hour. The clear solution on cooling deposits a copious mass of lustrous crystals of the crude phenylglycinamid-p-arsonic acid. Concentrated hydrochloric acid is then added until the mixture becomes 60 distinctly acid to Kongo red. The mixture is then filtered and the residue thoroughly washed with cold water. For purification this product is then suspended in several parts of water and sodium hydroxid, or other 65 alkali added until solution is complete. The

solution is then filtered and treated with an excess of acetic acid, which precipitates the free acid in pure form. Upon filtering and careful washing and drying of the residue a pure stable product is obtained. In the 70 above reaction the alkaline hydroxid may be substituted by any other suitable basic substance.

This new product with the following formula 75

80

is a colorless crystalline product which, 85 when heated in an open capillary tube, does not melt below 280° C. , and is sparingly soluble in cold water but may be recrystallized from hot water. It is readily soluble in alkali and alkali carbonate from which it is 90 reprecipitated by acids. Heavy metal salts give insoluble precipitates. It forms stable salts. The soluble metallic salts and particularly the sodium salt are recommended for use. The sodium salt is prepared as follows: 95

One part of the acid is suspended in two parts of water and, while stirring the mixture, sodium hydroxid solution is carefully added until solution of the acid is complete and the reaction of the solution is neutral to 100 litmus. Several volumes of 95 per cent. alcohol are then added while stirring the mixture. The sodium salt separates as a colorless lustrous crystalline substance. By filtering the mixture; washing the residue with a little 85 per cent. alcohol and drying it in the air, a stable salt containing approximately one-half molecule of water of crystallization is obtained. This salt is extremely soluble in water forming neutral solutions, and it is therefore especially suitable 110 for therapeutic use. By the substitution of potassium hydroxid or ammonia the corresponding salts can be made by the above process. 115

Example II.

N-phenylglycin-p-arsonic acid methyl ester of the following formula

120

is readily obtainable by the following process:

A mixture of 10 parts phenylglycin-p-arsonic acid methyl ester and 130

sonic acid 30 parts of dry methyl alcohol and 3 parts of concentrated sulfuric acid are boiled under a reflux for two hours. The ester separates as microscopic needles, on cooling the mixture and diluting it with water. This ester decomposes at about 270° with preliminary softening.

One part of the methyl ester is carefully added to three parts of concentrated ammonia water while the mixture is being stirred and chilled. A thick mass of crystals of the ammonium salt is first obtained which, after a short while, dissolves to a clear solution, as the reaction proceeds. After twenty-four hours the excess ammonia is removed, preferably *in vacuo*, and the residue diluted with water. An excess of acetic acid is then added, which precipitates the phenylglycinamid-p-arsonic acid in the pure characteristic form described in Example I. In Example II the homologous esters, such as the ethyl ester, can be used. The sodium salt is prepared as in Example I.

Example III.—N-(Phenyl-p-arsonic acid)-a-phenylglycin amid.

87 grams of p-aminophenylarsonic acid are dissolved in 400 cc. normal sodium hydroxid solution, and 68 grams phenylchloroacetamid and 500 cc. 95 per cent. alcohol are added. To facilitate the reaction 80 grams of sodium iodid are then added and the mixture is heated under a reflux for several hours. On cooling the mixture the reaction product crystallizes out. This, after filtration, is purified by redissolving it in dilute alkali or ammonia and reprecipitating it with acid. For conversion into the sodium salt, this is suspended in a small amount of water and sodium hydroxid added until solution is complete. This solution, which should be neutral to litmus, is then treated with sodium acetate to salt out the sodium salt. For final purification the salt is re-crystallized from 95 per cent. alcohol, from which it separates with approximately 4 molecules of water of crystallization. The salt is stable and dissolves easily in water.

The foregoing are a few examples of substances falling within the spirit and scope of our invention. It will be obvious to any one skilled in the art that many variations in the exact constitution of the substances described may be made without departing from the spirit and scope of our invention.

What we claim is:

1. As a new product, a soluble salt of an aromatic arsonic acid having in its molecule an α -aminoacylamin side chain, the aromatic nucleus being joined to the α -amino group in 60 said side chain, the acyl radical of said side chain containing a plurality of carbon atoms.

2. As a new product, a soluble salt of an aromatic arsonic acid having in its molecule 65 an α -aminoacylamin side chain having the general formula $-\text{NH}.\text{CHR}.\text{CON}'\text{R}''$, in which R is an alkyl or aryl or hydrogen and R' and R'' are alkyl or hydrogen, the aromatic nucleus being joined to the α -amino 70 group in said side chain.

3. As a new product, a soluble salt of an aromatic arsonic acid having in its molecule the glycaminid group $-\text{NH}.\text{CH}_2.\text{CONH}_2$, attached to the aromatic nucleus as a side 75 chain, the aromatic nucleus being joined to the α -amino group in the said side chain.

4. As a new product, a soluble salt of an N-phenylglycin-amid arsonic acid.

5. As a new product, a soluble salt of 80 N-phenylglycin-amid-p-arsonic acid.

6. As a new product, the sodium salt of an aromatic arsonic acid having in its molecule an α -aminoacylamin side chain, the aromatic nucleus being joined to the α -amino group in 85 said side chain, the acyl radical of said side chain containing a plurality of carbon atoms.

7. As a new product, the sodium salt of an aromatic arsonic acid having in its molecule 90 an α -aminoacylamin side chain having the general formula $-\text{NH}.\text{CHR}.\text{CON}'\text{R}''$, in which R is an alkyl or aryl or hydrogen and R' and R'' are alkyl or hydrogen, the aromatic nucleus being joined to the α -amino 95 group in said side chain.

8. As a new product, the sodium salt of an aromatic arsonic acid having in its molecule the glycaminid group $-\text{NH}.\text{CH}_2.\text{CONH}_2$, attached to the aromatic nucleus as a side 100 chain, the aromatic nucleus being joined to the α -amino group in the said side chain.

9. As a new product, the sodium salt of an N-phenylglycin-amid arsonic acid.

10. As a new product the sodium salt of 105 N-phenylglycin-amid-p-arsonic acid.
